(57) **CLAIM**

The ornamental design for a cake plate carrier, as shown and described.

DESCRIPTION

FIG. 1 is a top plan view of a cake plate carrier showing my new design;

FIG. 2 is a front elevation view thereof, where the back view is a mirror image thereto;

FIG. 3 is a left side elevation view thereof, where the right side view is a mirror image thereto; and,

FIG. 4 is a perspective view thereof.

The broken line portion of FIG. 4 is included to show unclaimed exemplary content subject matter only and forms no part of the claimed design.
